STAIR TREAD MAT

Hunter B. McKay, Belmont, Mass., assignor to Boston Woven Hose and Rubber Company,
Cambridge, Mass., a corporation of Massachusetts

Application June 12, 1952, Serial No. 20,155

Term of patent 14 years

(Cl. D9—6)

To all whom it may concern:

Be it known that I, Hunter B. McKay, a citizen of the United States, residing at 2 Colonial Terrace, Belmont, in the county of Middlesex and Commonwealth of Massachusetts, have invented a new, original, and ornamental Design for a Stair Tread Mat, of which the following is a specification, reference being had to the accompanying drawing, forming a part thereof, in which:

Fig. 1 is a perspective view of a stair tread mat embodying my new design; and

Fig. 2 is a fragmentary bottom plan view of the front portion of the mat.

I claim:

The ornamental design for a stair tread mat, substantially as shown.

HUNTER B. MCKAY.
